UNITED STATES PATENT OFFICE.

CHARLES C. KRIEBLE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

KNITTING MACHINE.

Application filed February 23, 1923. Serial No. 620,818.

To all whom it may concern:

Be it known that I, CHARLES C. KRIEBLE, a citizen of the United States, and resident of Norristown, in the county of Montgomery and State of Pennsylvania, have invented 5 certain new and useful Improvements in Knitting Machines, of which the following is a specification.

The invention is shown in connection with 10 a rib knitting machine of the latch needle type, though I do not limit myself to this class of machine in connection with all features of the invention.

The invention consists in the features and 15 combination and arrangement of parts hereinafter described and particularly pointed out in the claims.

In the drawings:

Figure 1 is a plan view of a portion of a 20 knitting head embodying the invention, showing, however, only two feeds of a multiple feed machine, one being active and the other inactive.

Fig. 2 is a side view of part of a knitting head with the improvements attached, the 25 needle cylinder, dial, dial cap and cylinder cam ring being shown only in outline.

Fig. 2 is a side view of a part of the cylinder cam ring, showing the means for automatically adjusting the needle raising and 30 stitch cams.

Fig. 3 is a view of a portion of the dial cap in elevation with certain of the mechanism which is mounted thereon, shown 35 partly in elevation and partly in section and showing also in section, and diagrammatically developed, a portion of the dial of the rib knitting machine with certain parts carried thereby.

Fig. 3 is a detail of Fig. 3.

Fig. 4 is a plan view of the needle dial of the rib knitting machine.

Fig. 5 is a sectional view of part of the needle dial, showing the cam and one of the pins for controlling the changes in the 45 yarn feeds.

Fig. 6 shows detail views of a cam and fork for operating the yarn guide finger, and yarn cutter.

Fig. 7 is a plan view of the star wheel and cam operated thereby.

Fig. 8 shows in perspective two views,

from opposite sides, of the cam which operates the yarn feeding, cutting and clamping mechanism.

55

Fig. 9 is a view of the yarn guide finger.

Fig. 10 is a view of an arm for operating the yarn shear blade.

Fig. 11 shows views of an arm for adjusting, automatically, the stitch cam of the 60 cylinder needles.

Fig. 12 is a detail view of a cam post or shaft.

The machine belongs to that class in which the needle carrier or carriers rotate. The 65 needle cylinder 1, the dial 2, and the dial cam support or cap 3 are shown merely in outline in Fig. 2, and these parts as they appear in the other figures are designated by similar reference characters.

70

The invention may be used in a machine having any desired number of feeds. There is a yarn guide finger 4 at each feed, this being pivoted at 5 to a bracket 6 fixed to the base of the stationary cam ring 7 of the 75 cylinder. This yarn guide finger is normally pressed down into feeding position, shown in Fig. 2 and at the right of Fig. 1, by a spring 8, and it is raised against the tension of this spring when this feed is to 80 be thrown out of operation, by a cam member 9 having an inclined surface 10 which, by riding over the tail end 11 of the yarn guide finger, will elevate its inner end and raise the yarn out of work and also so that 85 it will be cut by the shear blades, the movable one of which is shown at 12, and when cut, the end of the yarn will be held by a clamp 12' between itself and the blade, as is common practice.

90

A little before the yarn is lifted, cut and clamped at its loose or cut end, the raising cam of the cylinder needles and the wing cam of the dial needles are adjusted to retracted position so that the loops on the needles at this feed will not clear their latches, and hence will not knit off, as will be more fully described hereinafter.

95

For operating the wiper cam 9 it is mounted on a hub 9' turnable about a vertical axis 13 and having an arm 14 to which is pivotally attached a rod 14 which extends substantially radially of the machine and is pivotally connected at 15 to an arm 16

100

pivoted at 17 to a base plate 18 of a bracket 19, said base plate being secured to the dial cap or cam plate 3. The arm 16 has a finger 20 bearing on the edge of the upper 5 half of a cam 21. The cam is provided with a hollow hub 22, mounted on a vertical shaft or post 23 and connected thereto by a pin 24 on the post extending into a notch or slot 25 of the hub. The shaft is formed with 10 a flange 26 to which is pinned a star wheel *a* having four arms, two of which *a'* are in a horizontal plane above the plane of the other two arms *a''*. The two high arms are diametrically opposite each other, or substantially so, their straight front edges being in 15 the same radial plane, and the two low arms *a''* are likewise substantially diametrically opposite each other, so that the high and low arms alternate in position around the 20 star wheel. The vertical shaft at its lower end projects below the star wheel, as shown at 27, into the path of a cam 28, having an inclined upper face, said cam being carried by the dial 2. The lower end of the post 25 or shaft when in its lowermost position (Fig. 3 showing its raised position) projects into a groove 29 in the upper face of the needle dial, and the cam 28 is located in this groove with its high point flush with 30 the top of the groove. The needle dial also has two pins *b* and *c*, one behind the other, and at the same distance from the axial center *d* of the knitting head, about which center the needle cylinder and dial rotate. 35 These pins are spaced apart circumferentially of the dial and the cam 28 for raising the post or shaft 23 with its star wheel is located on a radial line passing between the two pins. The cam 28 is fixed to the dial 40 by its shank, which is screw threaded and is clamped by a nut, Fig. 5. The two pins *b* and *c* are in position to strike the arms of the star wheel in succession and by their combined action thereon they give the star 45 wheel a one-half revolution, one-quarter revolution for each pin, and consequently the cam 21 also will be given a one-half revolution at each feed changing operation. In this action the pin *b* will strike one arm, 50 i. e., one of the high arms *a'*, and give the star wheel a quarter turn, and the pin *c* will then strike the next arm of the star wheel, which is a low arm, and give the star wheel another quarter revolution. These actions 55 presuppose that the star wheel has been thrust down from its high or idle position shown in Fig. 3, so that one of the high arms *a'* is in the path of the pin *b*. The low arms are always in the same plane horizontally 60 with the pin *c*, whether the star wheel is in its high position, shown in Fig. 3, or in its lowered position, as will be presently described, so that the star wheel having been given a quarter turn by pin *b* striking the 65 high arm, the next quarter turn to complete

the desired half turn will be given by pin *c* striking the next arm, which is a low one. At about the time this latter action occurs, however, the cam 28 lifts the star wheel by 70 engaging with the lower end 27 of its shaft or post 23 to which it is fixed, and thus when the star wheel has been given its second rotary step movement it will have assumed the raised position of Fig. 3 with its high arms *a'* above the plane of movement of the 75 pins *b* and *c*, and with its low arm *a''* in the position to which it was moved and left by the pin *c*. Therefore as long as the post or shaft 23 with its star wheel remains in its raised position there will be no further revolution of the star wheel and the yarn feed controlled by this star wheel will not be changed by the travelling pins.

When the next change is to be made, whether this be throwing the yarn finger in 85 or out, the star wheel must be thrust downwardly so as to bring one of its high arms *a'* in line horizontally with the pin *b*. It must be noted here that in the previous movement of the star wheel it had been left in such a 90 position that it is only necessary to lower it in order that its upper arm *a'* may be located across the path of the pin *b* to be struck and operated thereby to give the star wheel its first quarter rotation and to 95 swing the next following low arm *a''* across the path of the next pin *c*, whereupon the star wheel will be given its second quarter turn and lifted to idle position again by cam 28. It will therefore be seen that the normal 100 position of the star wheel is up, and that when the pattern mechanism calls for a change at the feed controlled by said star wheel it is thrust down so that it will be given a half turn by the pins *b* and *c* acting 105 successively upon its high and low arms and the star wheel will again be in its elevated position as soon as its half turn movement is completed. The high arm *a'* and pin *b* initiate the rotary half turn of the 110 star wheel and the pin *c* and low arm *a''* complete the half turn, while the cam 28 elevates the star wheel to idle position in the condition it is left by the pin *c* and low arm *a''* so that it is ready again to go 115 through its two step rotary movement as soon as it is again lowered. For lowering the star wheel shaft 23 with the star wheel I prefer to employ pattern mechanism and flexible push connections, such as are disclosed in application for Letters Patent of the 120 United States filed by Kenneth Howie and William O. Taylor, April 3, 1922, Serial Number 549,253, in which the push connections consist preferably of closely coiled 125 wire members 29', guided in tubes one of which is shown at 30. These tubes are mounted rigidly on the machine in any suitable manner and they direct the flexible push rods down onto the upper ends of the 130

shafts or posts 23 of the star wheels, so that each time the pattern mechanism pushes one of these rods through its tube it will force the shaft 23 downwardly so that the feed 5 controlled by the star wheel of this post or shaft will be changed, whether this change be that of throwing the feed finger down or up. The tubes 30 are curved as shown in the application referred to and extend to 10 the pattern mechanism. There is one of these tubes for each feed and in the present machine they are held by set screws in the tops of the brackets 19, see Fig. 3^a. The shaft 23 is held in either its elevated or 15 lowered position by a suitable detent.

In the present case I have shown a friction device at 30', Fig. 3^a, pressed into adjustable engagement with the post or shaft by a spring and screw at 31. Detent means 20 are also provided to prevent rotary overthrow of the star wheel and its shaft, so that it will be restrained when its quarter turn movement has taken place. The hub 22 of the cam 21 is formed with indents 25 32 spaced 180° apart about its circumference and these indents are engaged by detent means of any suitable character, shown at 33. This will allow the hub, together with its cam, to be turned by pressure of 30 the pins *b* and *c* on the star wheel, but as soon as the pin positions the star wheel and is about to leave it, the detent will frictionally engage one of the indents and hold the cam and star wheel in this position 35 until positive pressure of one of the pins is brought to bear again.

The cam 21 has an upper and a lower portion or circumferential track. The upper track operates upon the arm 16 for controlling the throwing in and out of the 40 yarn finger and shear, and the lower circumferential track of this cam operates upon an arm 34 pivoted at 35 to the base 18 of bracket 19. This arm is connected 45 to a rod 36 extending substantially parallel with the rod 14, and it has fixed thereto a stud 37 engaging an arm 38 pivoted to the dial cap at 38' and having a screw or pin 39 passing down through a slot 40 in the dial cap and connected with the so called wing cam 40' of the dial needles for advancing them. When the wing cam is set in its outward position the dial needles will knit, but when this cam is retracted 55 inwardly it will not advance the dial needles far enough to make their loops clear their latches and hence these needles will not knit off, but they will pass this particular feed while simply holding their loops. They will knit at the next active feed. The radial outward movement of the 60 rod 36 will also operate a lever 41 to which it is connected at 42. This lever is pivoted at 43 to a bracket fastened to the fixed cam ring 7 of the cylinder needles, and this

lever has a foot portion 44 which lifts the post 45 of the cylinder needle raising cam 46, Fig. 2^a, to its normal position for advancing the cylinder needles for knitting. This normal position of the wing cam is 70 shown on the right of Fig. 1 and the raised or normal position of the cylinder needle raising cam 46 is indicated in Fig. 2^a, and also in Fig. 2, where the post 45 is indicated as raised. The position of the parts 75 at the right of Fig. 1 and in Figs. 2 and 2^a are those assumed during knitting. The yarn feed finger 4 is down in feeding position and the shear blade 12 is open and the wing cam and cylinder needle raising 80 cam are in their advanced position to advance the needles to take the yarn and knit.

The shear blade 12 turns about a post 48 and is connected to an arm 49 connected by a link 50 with an arm 51 loose on the post or axis 13 about which the wiper cam 9 turns. The connection between the link 50 and arm 51 is by a pin and slot 52 to allow lost motion, and the arm 51 has a pin in between the members of a fork 53 connected to and moving with the hub 9' of the wiper cam. The rod 14 has a spring 54 bearing at one end against the shoulder 55 of the rod and at its other end against a collar 56 loose on the rod. This collar is borne upon by a collar 57 of the stud or roller 37, and this collar is fixed to the rod 36. 95

The two arms 16 and 34 embrace the cam 21 and they, together with the collars 56 and 57 and the spring 54 and rods 14 and 36 and the springs at the raising and stitch cams, cooperate to give the various parts their movements in proper time. 100

When the rod 36 is moved radially outward by the high part of the lower track of the cam 21, the low part of the upper track of the cam, that is, the part nearest the center, will be opposite the arm 16, and this outward movement of the rod 36 110 will cause its collar 57 to press upon collar 56 and this will be transmitted through the spring 54 to force the rod 14 outwardly under control of the arm 16 riding upon the upper track of the cam 21, but if arm 16 rides upon a high part of its cam track the rod 14 can still move inwardly because the spring 54 will yield. This spring incidentally will also react through its loose collar 56 upon the collar 57 fixed to rod 36, so that when a low part of the cam 21 comes opposite the arm 34, the latter will move inwardly and thus the spring 54 will assist in operating the dial wing cam and cylinder raising cam to their retracted 120 or tuck position. 125

While it is true that the spring 54 has the incidental function just stated, it is to be noted that the main thing which keeps the arm 34 against its cam is the springs 130

at the raising and stitch cams of the cylinder reacting through the lever 41 and rod 36.

There is a spring at the needle cams. 5 These are shown at 58 for the wing cam, 59 for the cylinder stitch cam, and 60 for the cylinder needle raising cam.

The cycle of operation of the parts controlled by the cam 21 is as follows, see Fig. 10 7.

While lever 34 is at point *e*, which is one normal position, the needle raising cam is up in normal position and the stitch cam is down in normal position.

15 The yarn finger is down in feeding position.

At this time also lever 16 is at point *f*, i. e., nearest the center of the cam 21, and the yarn feed finger is now down in feeding 20 position and the shear blade is open, all as shown at the right of Fig. 1 and in Fig. 2.

The cam rotates in the direction of the arrow and makes a half turn at each feed changing action.

25 When point *g* reaches lever 34 the latter snaps inwardly due to the springs at the several needle cams, and thus the wing cam and the needle raising cam of the cylinder will be set in retracted position to avoid 30 clearing their loops back of their latches, and the needles in passing this feed will not knit but will simply hold their loops. When this happens the shears are still open and the yarn finger is still in feeding position, but soon the incline *h* and point *i* acting on the arm 16 raises the yarn feed finger. The shear remains open a little longer, however, because of the lost motion due to the 35 slot in its link connection and also the lost motion provided by the pin between the forks of arm 53. When point *j* reaches arm 40 the shear closes and the cycle of rendering the feed inactive is complete, the parts then being as on the left of Fig. 1.

45 In bringing the feed into operation again from the position shown on the left of Fig. 1, the cam 21 makes a half turn in the same direction as before, see the arrow, and the first effect is that the incline surface from *k* to *l* moves past arm 16, allowing this to come in under the action of the spring or rod 14, which finds a backing against its loose collar 56 now held against the collar 57 fixed on the parallel rod 36. This rod 50 36 is moving radially outward because its arm 34 is being pushed by incline *m*, and its fixed collar 57 is pushing against the loose collar 56 on rod 14 and transmitting power 55 through the spring. This will cause rod 14 to swing the cam 9 from over the tail of the yarn feed finger, which will now lower by its spring 8. The clamp will not open yet owing to the lost motion at the fork and pin 60 53 and to the slot and pin connection 52. This means also that the shear blade will

not open yet, but the clamp of which the shear forms a part will maintain control over the cut end of the yarn, until the yarn is taken by the needles.

While this lost motion is taking place at 70 the clamp, the surface at *m* is acting on arm 34 as just stated, and hence the wing cam and cylinder needle raising cam are being restored to normal position for knitting by moving the rod 34 outwardly. This movement of the rod continues until the point *n* is reached, when the cams are fully in position for knitting.

The shears are opened when the point *o* passes the arm 16. The yarn finger previous to the opening of the shears had lowered to feeding position.

Briefly stated the sequence of operations is:

Sequence of operation.—In throwing a 85 feed out the order of operation is:

1st; the wing cam and cylinder raising cam are set in retracted position, i. e., partly retracted, at the same time the stitch cam of the cylinder is set in retracted position 90 so as not to strain the loops held by the needles which do not knit at this feed.

2nd; the yarn feed finger is lifted to raise the yarn from the needles.

3rd; the cutter and clamp closes.

Operation in bringing a feed into operation:

1st; yarn finger is lowered.

2nd; the cams (wing, cylinder raising and cylinder stitch cams) are set in knitting position.

3rd; clamp opens.

The stitch cam is adjusted to slightly retracted position in order not to strain the loops held by the needles which pass this cam without knitting and this is done automatically by the lever 61 pivoted at 62 to a post fixed to the cylinder cam ring. This lever at one end rests on top of the post of the needle raising cam 46 and at its other end it has an adjustable screw member 63 to bear on the top of the post of the stitch cam, so when the needle raising cam moves down to its tucking position the stitch cam will move up under pressure of its springs 59 and will thus not strain the formed loops on the needles.

While I have shown features of my invention in connection with a rib knitting machine, I do not limit myself as to all of them as applied to this type of machine. Nor do I limit myself to a machine of the latch needle type. The drawings and specification herein are illustrative of the principle of my invention and are not to be considered, as limiting the invention to the mechanism shown, the scope of the invention being defined by the appended claims.

The term feed, as used herein, refers generally to the station and the appliance lo-

cated there for directing and forming the yarn into loops. In a two-feed machine, there would be two of these stations where the yarns are fed to the knitting devices located thereat, and in a three-feed machine there would be three such stations.

What I claim is:

1. In combination in a circular rib knitting machine, having a rotary needle cylinder and dial, a plurality of feeds disposed at separated points about the knitting head, a plurality of controlling means, one for each feed supported by the dial cap and in part extending therethrough, radial connections extending therefrom to the several feeds and means for operating said controlling means in prescribed order for changing the feeds, said means including contact means travelling with the needle dial, substantially as described. 10
2. In combination in a circular rib knitting machine, having a rotary needle cylinder and dial, a plurality of feeds disposed at separated points about the knitting head, a plurality of controlling means, one for each feed including members arranged between the dial cap and rotary needle dial, with connections extending up through the dial cap and thence radially to the feeds, from and operated by said members, means carried by the needle dial for operating said members, and means for determining the time and order of operation of the said members by the dial carried means, substantially as described. 25
3. In combination in a circular rib knitting machine having a rotary needle cylinder and dial, a plurality of feeds disposed at separated points about the knitting head, a plurality of star wheels, one for each feed, arranged between the dial cap and dial, means travelling with the dial for operating the star wheels, connections extending from the star wheels up through the dial cap and thence to the feeds, means travelling with and supported on the rotary dial for operating the star wheels and means for determining when the said means will operate the star wheels for changing the feed, substantially as described. 40
4. In combination in a rib knitting machine, a rotary needle cylinder and dial, a plurality of feeds disposed about the knitting head, star wheels arranged beneath the dial cap, means travelling with the needle dial for operating the star wheels, cams operated by the star wheels and arranged on the upper side of the dial cap, connections extending from said cams outwardly and operated thereby for changing the feeds, and means extending down through the dial cap for changing the level of the star wheels, substantially as described. 55
5. In combination in a rib knitting machine a rotary needle cylinder and dial, a plurality of feeds on the under side of the dial cap, having high and low arms, contact means on the rotary dial for turning the star wheels by striking said arms, means extending down through said dial cap for lowering the star wheels, so that the upper arms thereof will be struck by said contact means to turn the star wheels, contact means travelling with the dial for operating star wheels through their lower arms, cam means carried by the rotary dial for raising the star wheels so that their upper arms will be above the path of travel of the contact means, and connections from the star wheels to the feeds, substantially as described. 70
6. In combination in a circular rib knitting machine, a plurality of feeds, means carried by the needle dial for controlling said feeds, and connections therefrom to the feeds including members to be struck by said travelling means with connections extending up through the dial cap and thence radially to the feeds, means for setting said members into the path of said travelling means consisting of posts extending through said dial cap and flexible push rods bearing on the upper ends of said posts for forcing the same downwardly and tubes for guiding said push rods, substantially as described. 80
7. In combination in a circular knitting machine, a plurality of feeds, means for controlling them, including members adjustable to different levels and supported on a fixed part of the knitting head, means travelling with a rotary part of the knitting head for operating said members, connections between said members and the feeds for changing them, and means for changing the level of the said members including posts extending up through the fixed part of the knitting head and flexible push members bearing on the upper ends of said posts and tubes for grinding said push members, substantially as described. 90
8. In combination in a circular rib knitting machine, a plurality of feeds, connections for operating said feeds extending substantially radially of the machine towards the axis thereof over the dial cap and thence through said cap, means travelling with the dial for operating said connections and means for determining the times and order of operation of said connections including posts, one for each feed extending through the dial cap, flexible push means bearing on the upper ends of said posts, and guide tubes for said flexible push means, said posts when pushed downwardly moving a part of the said connection into the path of the travelling means on the dial, substantially as described. 105
9. In combination in a circular rib knitting machine, a plurality of feeds, connec- 115

- tions for operating said feeds, extending substantially towards the axis thereof over the dial cap and thence through said cap, means travelling with the dial for operating said connections and means for determining the times and order of operation of said connections including posts, one for each feed, extending through the dial cap, and means for pushing said posts downwardly 10 to throw a part of said connection into the path of said travelling means, substantially as described.
10. In combination in a circular knitting machine, a plurality of feeds, a star wheel for each feed, having a pair of high and a pair of low arms thereon, sleeves splined to said star wheels and mounted to turn in a fixed part of the knitting head, a pair of pins for rotating said star wheel, 15 said pins being arranged one behind the other on a travelling part of the knitting head, posts carrying the star wheels and movable through the sleeves, means for depressing the posts to bring the upper arms 20 of the star wheels in line with the first travelling pin, a cam on the rotary part of the machine between the pins for raising the posts, the second pin turning the star wheels by engaging the low arms thereof, cams on 25 the upper ends of the sleeve and connections operated by said cams for throwing the feeds in or out of work, substantially as described.
11. In combination in a circular knitting 30 machine a plurality of feeds each including a movable yarn guide and a yarn cutter and clamp, a needle advancing cam at each feed, and means for throwing the feeds in and out of work, including a connection for operating the yarn finger and cutter to lift the yarn from the needles and cut and clamp it and a connection for adjusting the needle advancing cam to retracted position, said 35 connections including radial rods, one for the yarn fingers and cutters and one for the needle advancing cams, rotary cams, levers operated by said cams and connected to said rods, and means for operating said cams, substantially as described.
12. In combination in a circular rib knitting 40 machine, a plurality of feeds, with a movable yarn guide, a yarn cutter and clamp at each feed, a cylinder needle advancing cam, a dial wing cam, a connection 45 at each feed for operating the yarn finger and cutter, a radially extending connection at each feed for operating both the wing cam and the cylinder needle advancing cam, and means for operating said connections, substantially as described.
13. In combination in a circular rib knitting 50 machine, a plurality of feeds spaced apart around the machine with a single yarn guide finger at each feed, movable to 55 and from feeding position, a yarn cutter 60 and clamp at each feed, connections extending radially inward from the feeds for operating the feed fingers and yarn cutter, connections extending radially of the machine above the dial cap for operating the dial wing cam and the cylinder needle advancing cam at the various feeds, means for operating said connections mounted in the dial cap and having members at their lower ends, contact means carried by the rotary 65 needle dial for operating said members and a pattern connection for each feed controlling mechanism to determine the order of their operation by the said contact means, substantially as described.
14. In combination in a circular rib knitting 70 machine, a plurality of feeds spaced apart about the machine, a series of connections extending inwardly from the feeds above the dial cap, means mounted in the dial cap and having contact members exposed at the lower ends thereof for operating said connections, contact means on the upper side of and travelling with the dial for operating the contact means first mentioned, and pattern controlled connections, one for each feed for setting the contact 75 means of the said connections into position to be operated by the said dial carried contact means, substantially as described.
15. In combination in a circular knitting 80 machine, a plurality of feeds with a movable yarn finger at each feed, a connecting rod extending from each yarn finger inwardly towards the center of the machine, needle advancing cams, a connecting rod extending radially of the machine for operating said needle advancing cam to retracted position when the yarn finger is thrown out of work, a cam for each pair 85 of connecting rods, belonging to one feed and levers, one for each rod of each pair, one arranged on one side of the cam and the other arranged on the other side of the cam, said cam having two cam tracks, one for each lever and means for operating the 90 cams, substantially as described.
16. In combination in a circular knitting 95 machine, a plurality of feeds with a movable yarn finger at each feed, a connecting rod extending from each yarn finger inwardly towards the center of the machine, needle advancing cams, a connecting rod extending radially of the machine for operating said needle advancing cam to retracted position when the yarn finger is thrown out of work, a cam for each pair of connecting rods belonging to one feed, and levers, one for each rod of each pair, one 100 arranged on one side of the cam and the other arranged on the other side of the cam, said cam having two cam tracks, one for each lever, and means for operating the 105 cams, a spiral spring on the connecting rod of the yarn fingers bearing at its outer 110
- 120
- 125

end on a fixed shoulder of said rod and at its inner end on a loose collar, the companion rod of each pair leading to the needle cam, having a collar fixed thereon 5 bearing on the loose collar to compress the spring and keep the lever of the yarn finger connection against the low part of its cam when the other lever is riding against the higher part of its cam track, substantially as described.

17. In combination in a circular knitting machine, a plurality of feeds, with movable yarn feeding means at each feed, a cylinder needle raising cam, a radial rod for 15 operating the feeding means at each feed, a radial rod for operating the needle raising cam at each feed, a lever interposed between said rod and cam, and means for operating the rods, substantially as described.

18. In combination in a circular rib knitting machine, a plurality of feeds, a movable yarn finger at each feed, a yarn cutter and clamp at each feed, a radial rod 20 at each feed for operating said yarn finger

and clamp, a second radial rod, at each feed, wing cams, a connection between said last named rods and the wing cams and bell crank lever connections between said rods and the needle raising cams, a cam 30 for each feed for operating the pair of rods at each feed, said cam being mounted on the upper side of the dial cap, and a connection for each of said cams for operating them, extending down through the dial 35 cap, and having a contact member at its lower end, contact means on the upper side of the rotary dial for operating said contact means first mentioned and a pattern controlled connection for each feed including a vertically movable post connected to the contact means first mentioned for setting it into line with the travelling contact means of the dial and flexible pushers with guide tubes therefor, one for each post, substantially as described.

40 In testimony whereof I affix my signature.

CHARLES C. KRIEBLE.
